GRENADE THROWING TUBE

Wayne Gibbons, Camp Custer, Mich.

Application August 7, 1937, Serial No. 157,875

4 Claims. (Cl. 124—5)

(Granted under the act of March 3, 1883, as
amended April 30, 1928; 370 O. G. 757)

This invention described herein may be manufactured and used by or for the Government for governmental purposes, without the payment to me of any royalty thereon.

This invention relates generally to throwing tubes for grenades, but more particularly to a throwing tube wherein the fuse cap of the grenade is ignited and the grenade released by centrifugal force on operation of a manually controlled latching mechanism.

One object of the invention is to provide a throwing tube which increases the range and the accuracy with which the grenade may be thrown.

Another object of the invention is to provide a throwing tube which may be safely transported and handled without danger of accidental discharge of the grenade.

Still another object is to provide an improved throwing tube having few working parts and one which may be easily and cheaply manufactured.

With these and other objects in view this invention consists in certain novel details of construction, combination and arrangement of parts, to be more fully hereinafter described and claimed.

Referring more particularly to the accompanying drawing in which corresponding parts are indicated by similar reference characters—

Fig. 1 is a top plan view of the throwing tube;

Fig. 2 is a side elevation of the throwing tube partially in section, showing both the construction of the tube and an improved type of grenade which may be used therewith;

Fig. 3 is a top plan view of the grenade chamber and stem;

Fig. 4 is a sectionized view taken on the line 4—4 of Fig. 2; and

Fig. 5 shows a plan view of the striker and release spring;

Fig. 6 is a perspective view of the striker arm lever;

Fig. 7 is a perspective view of the grenade release lever;

Fig. 8 is a sectionized view taken on the line 8—8 of Fig. 2, and

Fig. 9 is an end view of the assembled grenade throwing tube.

Briefly stated, the throwing tube comprises a grenade chamber 1, which may be formed of seamless alloy steel tubing, the chamber being constricted at one end to form a stem 2 for the attachment of a handle 3. The grenade chamber is longitudinally corrugated, as indicated by the numeral 4 in Fig. 2, to reduce frictional contact with the grenade 5 and to prevent fouling with

dirt, and to thereby provide an uninterrupted smooth path over which the grenade can slide when being thrown by the operator.

At the rear of the grenade chamber 1 are mounted bracket members 6 and 6', which support a striker and a release mechanism, rotatably mounted on a shaft 7 which is held by the brackets in a normal position to the longitudinal axis of the grenade thrower. On the shaft 7 are rotatably mounted a weighted striker arm lever 8 and a grenade release lever 9.

The striker mechanism comprises a curved striker arm lever having a longitudinal rectangular opening 10 forming lateral bearing members 11 and 11' on either side thereof which are drilled at 12 and 12' for the reception of the shaft 7. At the forward end of the lever is formed a weight arm 13 and at other end a striker arm or hammer 14 provided with a striker pin 15. The striker arm or hammer 14 projects through the forward portion of opening 16 in the stem 2, with the striker pin 15 positioned behind the cap 17 of the grenade 5, so that when the inertia of the weight arm 13 rotates it outward from the grenade chamber the hammer 14 will move the striker pin 15 forward against the cap 17 of the grenade 5. It will be noted that the striker arm lever 8 is fulcrumed nearer the extremity of the hammer 14 to proportionately increase the length of the weight arm 13 and thus provide sufficient force to the movement of the striker pin to ignite the fuse cap 17 of the grenade 5.

The shaft 7 also provides a fulcrum for the releasing lever 9 which is centrally pivoted thereon and provided at its forward end with a normally vertically disposed lug 18, adapted to project through the opening 19 in the grenade chamber 1 and to engage a circular groove 20, in the exterior surface of the grenade 5, and thus retain the latter within the chamber 1.

A coil spring 21 encircles the shaft 7 and is attached at one end to the striker arm 14 of the weighted striker arm lever 8, and at the other end to the grenade release lever 9. This spring is adapted to operate the release lever as will be further described.

In the forward portion of the stem 2 is mounted a manually operated latching member comprising a central shaft 22, at one end of which is formed a normally projecting contact arm 23, and at the other end is attached a knurled roller 24. The central shaft 22 of the latching member is rotatably mounted within a longitudinal bearing 25 attached to the inner surface of the stem 2, so that the periphery of the knurled roller 24 par-

tially projects through the opening 26 in the handle.

Although various types of grenades may be used with the throwing tube a grenade which may be easily and cheaply manufactured and one which bursts with less resistance is illustrated in Fig. 2. This grenade, indicated by the numeral 5, is composed of laminated paper 27, into which the shrapnel 28 is embedded. The grenade 5 is provided with a fuse assembly 29, which consists of a primer 30 and a fuse 31. This fuse assembly is fastened permanently within the grenade. As the grenade ruptures easily along the lines determined by the position of the shrapnel, the costly high explosive filler may be reduced without impairing its effectiveness. This type of grenade may also be shipped fused, and can be handled in the same manner as ammunition for the service rifle and pistol.

20 In the operation of the throwing tube the contact arm 23 is moved out of the path of the grenade release lever 9 by rotation of the knurled roller 24, the tube is swung in an arc starting from the vertical and terminates at the angle determined by the range. Inertia acting on the weighted striker arm lever 8 actuates the hammer thereby causing the striker pin to rupture the cap 17. As the hammer moves to its firing position the lever 9 is operated to release the grenade.

30 In this operation it will be noted that the inertia of the weight arm 8 first increases the angle between the striker arm 14 and the rear arm of the release lever 9, thus putting the coil spring 21 under tension, and as the spring tends to resume its normal position it raises the forward arm of the release lever 9, extracts the lug 18 from the circular groove 20 in the grenade 5 and releases the same from the chamber 1.

When the throwing tube is not in use it may be 40 carried with its grenade chamber pointing downward, so that the weight arm 13 overhangs the arm of the release lever 9 provided with the projecting lug 18. In this position the weight arm retains the lug 18 within the circular groove in 45 the grenade 5, thus providing a safety factor against accidental release and also firing of the grenade, since in order to release and fire the same the weight arm must be thrown back from the outer wall of the grenade chamber 5.

50 Having described my invention, what I claim as new and desire to secure by Letters Patent, is:

1. A grenade throwing tube comprising in combination a corrugated grenade chamber adapted to receive a circumferentially grooved grenade, a 55 stem, a handle attached to said stem; a firing mechanism comprising a weighted bell-crank lever provided with a hammer and a firing pin; a grenade release mechanism comprising a centrally fulcrumed lever, one arm of which is provided with a lug adapted to engage the circumferential groove in said grenade, a coil spring, attached at its ends to the firing mechanism and the releasing mechanism adapted to resiliently couple

the same, and a manually operated latching device adapted to control the operation of said releasing mechanism.

2. A grenade throwing tube comprising in combination a corrugated grenade chamber, open at one end and adapted to receive a circumferentially grooved grenade; brackets mounted on said bearing chamber and a shaft supported by said brackets, a stem formed at the other end of said chamber, a handle attached to said stem; a firing mechanism comprising a weighted bell-crank lever, formed with a hammer member supporting a striker pin, and provided with lateral bearing members drilled for rotatable mounting on said shaft, a grenade release mechanism comprising a centrally fulcrumed lever, one arm of which is provided with a lug adapted to engage the circumferential groove in said grenade, a coiled spring around said shaft adapted to resiliently couple the firing mechanism and the releasing mechanism, and a manually operated latching device adapted to control the operation of said releasing mechanism.

3. A grenade throwing tube comprising in combination a corrugated grenade chamber adapted to receive a circumferentially grooved grenade, a stem, a handle attached to said stem, a firing mechanism comprising a weighted bell-crank lever provided with a hammer and a firing pin; a grenade release mechanism comprising a centrally fulcrumed lever, one arm of which is provided with a lug adapted to engage the circumferential groove in said grenade, a coil spring attached at its ends to the firing mechanism and the releasing mechanism adapted to resiliently couple the same, and a manually operated latching device comprising a rotatable shaft provided with manually rotated roller and a contact arm adapted to releasably engage said releasing mechanism.

4. A grenade throwing tube comprising in combination a corrugated grenade chamber open at one end and provided with an opening in its wall, said chamber being adapted to receive a circumferentially grooved grenade, a stem, a handle attached to said stem; a firing mechanism comprising a bell-crank lever provided with a weight arm and a hammer supporting a firing pin; a grenade release mechanism comprising a centrally fulcrumed lever, one arm of which lies intermediate the weighted arm of said firing mechanism and the outer surface of said grenade chamber, said arm being provided with a normally disposed lug adapted to project through said opening in the wall of the grenade to engage the circumferential groove in said grenade; a coil spring attached at its ends to the firing mechanism and the releasing mechanism adapted to resiliently couple the same, and a manually operated latching device adapted to control the operation of said releasing mechanism.

WAYNE GIBBONS.
